UNITED STATES PATENT OFFICE.

WILLIAM T. BARRATT, OF BENNINGTON, VERMONT, ASSIGNOR TO
CHARLES COOPER, OF BENNINGTON, VERMONT.

KNITTING-MACHINE NEEDLE.

No. 825,017.

Specification of Letters Patent.

Patented July 3, 1906.

Application filed December 6, 1905. Serial No. 290,547.

To all whom it may concern.

Be it known that I, WILLIAM T. BARRATT, a citizen of the United States, residing at Bennington, in the county of Bennington 5 and State of Vermont, have invented new and useful Improvements in Knitting-Machine Needles, of which the following is a specification.

This invention relates to that class of knitting-machine needles and jacks in which the needle is so formed that it may be attached to or detached from the jack by moving the same laterally with relation to the flat side faces of said jack, but which cannot be detached from the jack by moving the needle away from the rear edge of the jack in a direction parallel to the side faces of said jack.

The object of the invention is to provide a needle of the class hereinbefore referred to 20 which may be easily and cheaply manufactured and in which the stock from which the needle is made is not subjected to any abrupt bends, but when the needle is completed the butt will be of the same diameter throughout 25 as the shank of said needle and the metal from which the needle is made will not be crystallized by the process of manufacture.

The object of the invention is, further, to provide a needle having a butt so formed and 30 constructed as to lock the needle securely in the jack in the manner hereinbefore set forth without necessitating extreme accuracy in the length of the needle-butt as compared with the length of the slot in the needle-jack 35 which is adapted to receive said butt.

The invention consists of a knitting-machine needle formed and constructed as set forth in the following specification and particularly as pointed out in the claims thereof. 40 The invention further consists of a knitting-machine needle formed and constructed as hereinafter set forth and particularly as set forth in the claims, in combination with a jack provided with a slot formed to receive 45 the curved butt of said needle.

Referring to the drawings, Figure 1 is a side elevation of my improved knitting-machine needle and jack, the same being shown enlarged. Fig. 2 is a section taken on line 22, 50 Fig. 1.

Like numerals refer to like parts throughout both views of the drawings.

In the drawings, 5 is the knitting-machine needle, and 6 the jack. 7 is the shank of said

needle, and 8 the butt thereof, said butt extending transversely of said shank and bent to form a reverse curve consisting of the curved portions 9 and 10. The curved portion 9 terminates at one end thereof in the shank 7 at the bottom of said shank. The 60 jack 6 is provided with a slot 20, formed to receive said curved butt 8, said slot being shown in the drawings, Fig. 1, as slightly longer than the butt for the purpose of illustration. 65

The back edge of the jack 6 is cut away at 11 the diameter of the shank 7, so that the rear edge of the lower part of the jack and the rear edge of the needle 7 are brought into alinement. In attaching the needle 7 to the 70 jack 6 or detaching the same therefrom said needle is moved laterally with relation to the side faces 12 of said jack, and it will be seen that it will be impossible to separate the needle from the jack by moving it in the direction of the arrow, Fig. 1, or to attach the needle to said jack by moving the same in a direction opposite to that of said arrow, so that said needle is firmly locked to the jack 6 when said parts are located in the grooves or 80 tricks of a knitting-machine. 75

It will be noted that the lower edge of the slot 20 in said jack projects upwardly at its back end above the bottom of the butt 8 and bears against the end and back side of the 85 curved portion 9 of said butt, forming a support for the shank, which greatly strengthens the needle at this point and tends to hold the shank 7 firmly pressed against the back edge of the jack 6. 90

The advantages derived from my improved construction of knitting-machine needles are as follows: First, the curved formation of the butt where it adjoins the shank at 9 and also the other curved portion 10 there- 95 of are not sufficiently abrupt to cause the metal to become crystallized either in the manufacture of the needle or in its subsequent practical use; second, the needle is firmly locked to the jack, as hereinbefore described; third, the curved formation of the butt forms, in effect, a spring which performs the function of holding the shank of the needle firmly pressed against the butt of the jack 6; fourth, the length of the butt of the needle is 100 not necessarily of exactly the same length as that of the slot 20 in the jack, so that extreme accuracy in the length of said butt or in the 105

distance at which the end of said butt terminates from the shank 7 is eliminated.

Having thus described my invention, what I claim, and desire by Letters Patent to secure, is—

1. A knitting-machine needle, comprising in its construction a shank and a butt, said butt extending transversely of said shank and bent to form a reverse curve, said reverse curve terminating at one end thereof in said shank.

2. A knitting-machine needle, comprising in its construction a shank and a butt, said butt extending transversely of said shank and bent to form a reverse curve, said reverse curve terminating at the bottom of said shank, and a jack provided with a slot, formed to receive and fit said curved butt.

3. A knitting-machine needle, comprising in its construction a shank and a butt, said butt extending transversely of said shank and bent to form a reverse curve, said reverse curve terminating at the bottom of said shank, and a jack provided with a slot, formed to receive and fit said curved butt, the lower edge of said slot projecting upwardly at its outer end above the bottom of said butt and forming a support for said shank.

In testimony whereof I have hereunto set my hand in presence of two subscribing witnesses.

WILLIAM T. BARRATT.
